COMBINED ELECTRIC LAMP BASE AND SHADE SUPPORT THEREFOR

Meyer W. Temkin, Highland Park, Ill.
(1430 W. Wrightwood, Chicago, Ill.)

Filed Dec. 6, 1963, Ser. No. 77,701

Term of patent 3½ years

(Cl. D48—20)

FIG. 1 is a side elevational view of the combined electric lamp base and shade support therefor showing my new design;

FIG. 2 is a rear elevational view thereof;

FIG. 3 is a front elevational view thereof; and

FIGS. 4 and 5 are sectional views taken along lines 4—4 and 5—5 of FIG. 2.

The shade, bulb and socket are shown in broken lines for illustrative purposes only.

I claim:

The ornamental design for a combined electric lamp base and shade support therefor, substantially as shown and described.
